UNITED STATES PATENT OFFICE.

GILBERT R. ELLIOTT, OF BOSTON, MASSACHUSETTS, ASSIGNOR OF ONE-HALF TO MILTON CLARK, OF SAME PLACE.

CASH AND PARCEL CARRIER.

SPECIFICATION forming part of Letters Patent No. 278,658, dated May 29, 1883.

Application filed April 27, 1883. (No model.)

To all whom it may concern:

Be it known that I, GILBERT R. ELLIOTT, a resident of Boston, in the county of Suffolk and State of Massachusetts, have invented certain new and useful Improvements in Cash and Parcel Carriers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My improvements relate to that class of inventions known as "cash and parcel carriers" for warehouses, its objects being to provide means whereby articles can be transported from one place to another by a device which is adapted to travel a cable-way; and to this end my invention consists in the construction of a suitable carrier or frame which is suspended on a wire or cable-way by grooved wheels; and it also consists in the construction and operation of a tray which is designed to be fitted automatically to its seat, or, in other words, to the base of said frame and retained thereat, and enabled to be detached therefrom at will, the whole to be operated by suitable spring-actuated mechanism located and arranged within said tray; and my invention finally consists in a spring brake and check, to be located at the ends of the cable, whereby the carrier is stopped or arrested from further travel and detained until released by the operator, all of which will be more particularly described hereinafter.

In the drawings, Figure 1 represents a vertical side elevation of my improved device, suspended on a cable, to the end of which is affixed the brake. Fig. 2 is a plan view of the tray, illustrating the arrangement and operation of the spring mechanism. Fig. 3 is an end view of the carrier complete; and Fig. 4 is a longitudinal sectional view, on the line xx , Fig. 2, of the tray and mechanism by which it is locked to its place on the base.

Reference being had to the letters of reference, A represents the carrier proper, which is suspended on a wire or cable, a , by grooved wheels B , arranged between the hanger-rods C , projecting upward from the base b of the

frame. This base b has entirely surrounding it downwardly and outwardly curved or flaring sides D , those at the ends having lengthened slots c , the object of which formed sides and slots will be described more particularly hereinafter.

In the bottom of the tray E are lengthwise arranged two metal strips or bolts, d , d' , which are bent or formed at their outer ends into a latch, e , e' , which latch portions project through openings made in the side of the tray at the ends thereof. These tongues or bolts are each slotted at near their outer ends, and similarly slotted at nearer but not quite to their opposite or inner ends. The bolts being thus provided with slots adapts them to slide on pins i , i' in the bottom of the tray on which they work. At the extreme inner ends of the bolts they are slotted somewhat more elongated, as at k , they overlapping each other at this end slightly to permit the elongated slots to partly register, thus allowing them to communicate sufficiently for the projection therethrough of the enlarged pyramidal end of a rod or pin, F , up through said slots k . This pin F extends up through the knob or handle G on the bottom of the tray underneath, as shown in Fig. 4. Located to the side of the bolts, within the tray, is a bowed spring, H , the ends of which bear the bolts outwardly (this being their normal position) by pressing against pins h , h' , formed on said bolts.

I is a brake and stop block, which is to be located on the cable at the ends, and is for the purpose of arresting the travel of the carrier device when it has reached its destined point. This brake is secured on the cable by screws l , or in any suitable manner, and it consists of the block I , having extended outwardly therefrom at the top a steel or equivalent spring, K , secured and held in said block by nuts or otherwise. The spring, at its extremity, is upwardly curved or bent, which allows entrance of the wheels under it. The further it passes under the spring the tighter is its check or arrestment, and should the carrier be sent along with great force, sufficient to carry it to the very end of the cable, it will be met and allowed a yielding resistance by the rubber cushion L .

The operation is as follows: When cash or

any article is to be placed in the device for transportation, the operator simply takes hold of the knob G of the tray and pushes the rod F upward, which, by its pyramidal portion gradually widening outward, passes up through the slots k in the bolts and draws them inward, which releases their catch or fastening in the slotted ends of the flaring guides on the frame, thus detaching the tray from its seat. 5
 10 When the article has been placed in the tray, it is simply shut against the base (being directed thereto by the guides) and automatically locked. The ends of the bowed spring, bearing against the pins on the bolts, yield to the 15 upward force applied to the pin F, and when this is released the bolts are forced outward to their normal position.

While I have set forth certain spring-actuated mechanism for effecting the aforesaid objects, it will be obvious that I need not necessarily limit myself to the precise construction herein shown, as other and equivalent means may be employed without departing from the spirit of my invention. 20

25 What I claim is—

1. In a cash and parcel carrier, the combination of the frame, formed and constructed as herein described, with the tray, said tray having within its bottom suitable spring-actuated mechanism, whereby it is adapted to be automatically locked to the frame and detached therefrom, substantially as set forth. 30
2. In a cash and parcel carrier, the frame-base having the downward flaring sides, in combination with the tray, said tray having 35

within its bottom sliding bolts, which are adapted to be drawn inward by raising the pin herein described, whereby it is released and again forced outward by pressure of a spring, as set forth. 40

3. In a cash and parcel carrier, the tray having the knob and rod, the upper end of which is enlarged and pyramidal, in combination with the sliding bolts and spring, said bolts being formed at their outer ends with latches, and slotted, and having the pins, as described, the whole to be operated as set forth. 45

4. In a cash and parcel carrier, the bolts, formed and slotted as herein described, in combination with the tray and bowed spring, said tray having the pins on which the bolts are adapted to slide, which bolts are also provided with pins against which the spring outwardly presses, the whole to be operated in detaching the tray from its fastening by the manipulation of the rod which extends up through the knob on the bottom, as set forth. 50

5. In a cash and parcel carrier, the brake and stop block, consisting of the block having the rubber cushion and the outwardly-extending and upwardly-curved spring, as an article of manufacture. 55

In testimony that I claim the foregoing as my own I affix my signature in presence of two witnesses.

GILBERT R. ELLIOTT.
